Primary Examiner — Darlington Ly(74) *Attorney, Agent, or Firm* — Faegre Drinker Biddle & Reath LLP**(57) CLAIM**

The ornamental design for a motorcycle fairing as shown and described.

DESCRIPTION

FIG. 1 is a front-right side perspective view of a motorcycle fairing embodying our new design;

FIG. 2 is a front elevation view thereof;

FIG. 3 is a rear elevation view thereof;

FIG. 4 is a left side elevation view thereof;

FIG. 5 is a right side elevation view thereof;

FIG. 6 is a top plan view thereof; and,

FIG. 7 is a bottom plan view thereof.

The broken lines in the drawings illustrate portions of the motorcycle fairing that form no part of the claimed design.
